GLASS BLOWING MACHINE

August Kadow, Toledo, Ohio, and John E. McLaughlin, Alton, Ill., assignors to Owens-Illinois Glass Company, a corporation of Ohio

Application February 7, 1931. Serial No. 514,141

3 Claims. (Cl. 49—14)

Our invention relates to machines for blowing bottles, jars or other hollow glassware in molds, and particularly to means for supplying air to the articles in the finishing molds after they have been blown to their final form by the usual blowing operation.

After an article has been blown in the finishing mold to its final shape, it is necessary to retain it within the mold a sufficient length of time to cool it to such an extent that it will retain its shape after the mold is opened. During this cooling period, unless the air pressure is retained, there is a tendency for the glass to contract or shrink from the mold walls to a certain extent. This is objectionable both on account of the deformation of the article and because it lengthens the time required for cooling.

An object of the present invention is to provide means to overcome the above objections by supplying air to the blown articles after the usual blowing operation and build up a moderate pressure within the articles sufficient to prevent them from shrinking in the molds, and at the same time permit a circulation of the blowing air in a manner to hasten the cooling of the articles.

Other objects of the invention will appear hereinafter.

In the accompanying drawings:

Fig. 1 is a part sectional elevation view of a portion of an Owens suction type bottle machine to which the present invention is applied, and shows particularly a swinging frame carrying a finishing mold and associated mechanism.

Fig. 2 is a detail sectional elevation showing a "knock-out" arm and bottle holding disk carried thereby.

Fig. 3 is a sectional view of a valve controlling the supply of air to a "knock-out" arm.

Figs. 4, 5 and 6 are views, partly diagrammatic, showing the relation of the knock-out arm to the blown article at successive stages in the operation of said arm.

Fig. 7 is a part sectional elevation showing a pair of blowing heads and disks.

Fig. 8 is a view similar to Fig. 7, showing the relation of parts when the disks are seated on the bottles.

Fig. 9 is a sectional elevation on a larger scale of one of the blowing heads.

Fig. 10 is a section at the line X—X on Fig. 9.

Referring particularly to Fig. 1, the invention is shown as applied to an Owens type of suction gathering machine comprising a finishing mold 11 carried on a mold frame 12 mounted to swing

up and down on a continuously rotating mold carriage 13. A roll 14 on the frame 12 runs on a cam track 15 which is shaped to control the up and down swinging movement of the mold frame.

Mounted on the frame 12 is a rock shaft 16 which carries a rock arm 17 attached to the rock shaft by means of a head 18. The rock arm is formed at its outer end with a yoke 19 which carries blowing heads 20 and 21. The heads and the mechanism carried thereby are substantially alike in construction, except that the head 21 is preferably designed for adjustment up and down in the yoke 19. For this purpose, the head 21 is provided with external screw threads 22 engaging corresponding threads formed in the yoke 19. The head is adjustable up or down by rotating it and is held in adjusted position by a spring detent 23 engaging a ratchet 24 formed on the head.

Each of the blowing heads comprises an air operated piston motor including a piston 25 formed with a piston rod or tube 26 extending downward through the lower end of the blowing head or cylinder. Carried by each piston rod is a "knock-out" disk 27 provided with a hollow stem 28 extending upwardly therefrom and having a telescoping connection with the piston rod. The downward movement of the stem 28 relative to the piston rod or tube is limited by a stop collar 29 on said stem engaging a shoulder formed on said tube. A coil spring 30 surrounding the stem 28 is held under compression between the disk 27 and the tube 26.

Within the cylinder 21 is a coil spring 31 surrounding the tube 26 and bearing upwardly against the piston for holding the latter in its uppermost position except when air pressure is applied above the piston. The head 32 of the cylinder is formed with a central tubular extension or sleeve 33 in which a rod 34 is mounted. The rod 34 is screw threaded to engage corresponding screw threads formed in the upper end of the tube 33 to permit vertical adjustment of the rod. Such adjustment is effected by a hand wheel 35. A clamping nut 36 holds the parts in adjusted position. The rod 34 comprises a section 37 which extends downward through a central bore of a valve 38 mounted in the piston 25. The valve is formed with an annular tapered bearing surface 39 adapted to seat on a correspondingly shaped surface at the upper end of the piston rod 26. The valve is movable upward relative to the piston a limited distance determined by a collar 40 threaded within the piston.

The collar 40 has portions cut away to provide passageways 41 (Figs. 9 and 10) through which air is admitted when the valve is unseated, as hereinafter set forth. The upward movement of the piston 25 is limited by a stop 42 formed by a downward extension of the cylinder head 32.

The rock shaft 16 is mounted for reciprocation in the direction of its length and also for oscillating movement about its axis, as is customary with this type of mechanism. The lengthwise movements of said shaft are controlled by a stationary cam 43 on which runs a roll 44 carried by the shaft. The rocking movements of the shaft are controlled by a cam roll 45 mounted on the shaft and working in a cam slot 46 formed in a bearing sleeve 47 in which the rock shaft is mounted.

Air under pressure is supplied to the blowing heads from a suitable source of continuous air pressure supply (not shown) through an air line 48 extending to the bearing sleeve 47 and thence through the hollow shaft 16 and arm 17 to the blowing heads. A valve 50 (Figs. 1 and 3) within a valve casing 51 mounted on the mold carriage, is periodically opened by a stationary cam 52 operating through a bell crank 53, thereby supplying air under pressure to the line 48.

The operation is as follows:

During each rotation of the mold carriage, parisons are transferred to the finishing mold 11 and blown to finished form by a blowing head (not shown) in the usual manner. The "knock-out" arm 17 is then actuated by its cam 43 in two steps or stages, as indicated diagrammatically in Figs. 4 to 6. The first step consists in moving the rock shaft downward to an intermediate position (Fig. 4) by an inclined section 43^a of the cam. During this movement, the roll 45 is carried down the inclined section of the cam slot 46, thereby rocking the shaft and arm so that the disks 27 are brought to a position directly above and spaced from the bottles 54 in the finishing mold. The rock arm is held in this intermediate position for a predetermined length of time by a dwell portion of the cam 43. About the time this position is reached, the valve 50 is opened by its cam 52 so that air under pressure is supplied to the cylinders 20 and 21 above the pistons 25. The pistons are moved downward by the air pressure and cause the disks 27 to seat on the bottles (Fig. 5). The pistons may move downward a limited distance after the disks are seated, owing to the telescopic connection of the stems 28 with the hollow piston rods. As a piston 25 nears the limit of its downward movement, the valve 38 therein strikes a stop shoulder 55 on the stem 37, thus arresting the valve. The piston 25 continues to move downward a short distance after the valve is arrested, thus lifting the valve from its seat and permitting air under pressure to pass through the tube 26 and hollow stem 28 into the bottle 54. The downward movement of the piston is stopped by the collar 40 seating on the valve 38. The air pressure built up within the bottle when the valve 38 is opened is sufficient to hold the plastic glass in intimate contact with the mold walls and counteract the tendency of the cooling glass to shrink away from the mold walls. This materially shortens the time required for cooling the glass and also prevents distortion of the bottle by shrinkage. In order to vary the air pressure admitted to the ware, the point at which the valve 38 is opened as the piston moves down, is adjusted up or down by adjusting the stem 34 as heretofore described. Thus, if the stem 34 is adjusted downward, a comparatively

great air pressure above the piston 25 will be required to compress the spring 31 sufficiently to open the valve 38, and therefore, air under comparatively high pressure is admitted to the ware. By adjusting the stem 34 upward, less air pressure is required to compress the spring to a point where the valve opens, so that the air pressure admitted to the ware is reduced.

In order to prevent excessive air pressure and to maintain the pressure within the bottles at a predetermined moderate degree, the tension of the spring 31 is made sufficient to close or partly close the valve 38 and throttle the flow of air when the pressure in the bottle reaches a desired degree. Also, the spring 30 may be made of such tension that when the desired pressure is built up within the bottle it will react against the disk 27 and lift it sufficiently to relieve or prevent any excess pressure. This also permits a circulation of cooling air through the bottle while a substantially constant predetermined pressure is maintained within the bottle and assists in quickly cooling the glass.

This air pressure is preferably maintained until the bottles approach the discharging position. A section 43^b of the cam 43 then operates to pull the rock shaft downward from the Fig. 5 position to the Fig. 6 position. The valve 50 is closed about this time, thereby cutting off the supply of air to the bottles and relieving the pressure above the pistons 25. The finishing mold now opens, as indicated in Fig. 6, while the disks 27 hold the bottles in the usual manner. After the mold is opened, the rock shaft is lifted to release the bottles and permit them to be discharged from the machine.

Modifications may be resorted to within the spirit and scope of our invention.

What we claim is:

1. In a machine for forming hollow glass articles, the combination of a partible mold, a piston motor, a disk, a stem on the disk having a telescopic connection with the motor piston, said connection providing means whereby the disk is carried by the motor piston and movable thereby into position to seat on a blown article within the mold, means for supplying air under pressure to said motor and thereby actuating the piston, means cooperating with said motor and piston to provide an air passage leading from the motor cylinder through said disk, a valve in said piston, means to arrest the valve after the disk is seated on said article while the piston is moving toward said mold and before the piston has completed said movement toward the mold and thereby open the valve by the movement of the piston relative to the valve, and means providing an air passage leading from the valve to and through said disk.

2. In a machine for forming hollow glass articles, the combination of a mold, an air motor over the mold comprising a cylinder and piston, an article holding disk carried by the piston, means for supplying air under pressure to the motor and thereby actuating the piston and projecting said disk into engagement with a blown article in the mold, and means for moving the motor cylinder toward the mold after the disk has engaged said article and thereby positioning the parts for holding the disk on said article independently of air pressure within the motor and supporting the article during the opening of the mold.

3. In a machine for forming hollow glass articles, the combination of a mold, an air motor over the mold comprising a cylinder and piston,

5. In a machine for forming hollow glass articles, the combination of a mold, an air motor over the mold comprising a cylinder and piston, an article holding disk carried by the piston, means for supplying air under pressure to the motor and thereby actuating the piston and projecting said disk into engagement with a blown article in the mold, automatic means for lowering the motor cylinder after said engagement of the disk with said article, and means cooperating with the motor for holding the disk against said article independently of air pressure when the motor cylinder is in its lowered position.
6. The combination of a mold, an air motor comprising a cylinder and a piston above the mold, a piston rod, an article holding device carried by said rod and movable into holding engagement with an article in the mold when the piston is lowered, means for supplying air under pressure to the cylinder above the piston, means cooperating with the piston and piston rod to provide an air passage extending from the cylinder to said holding device, a valve in said air passage, means to open said valve when the piston is lowered, means for cutting off the supply of air to the cylinder, and automatic means for lowering the cylinder while said holding device is in engagement with the article in the mold.
7. A machine for forming hollow glass articles comprising, in combination, a rotating mold carriage, a mold rotating therewith, a rock shaft mounted to travel with the mold carriage, a rock arm on said shaft, a blowing device on the rock arm, a cam operable to move the rock shaft lengthwise to an intermediate position, means for causing the rock shaft during said lengthwise movement to rock about its axis and thereby swing the blowing device to a position over the mold, means cooperating with said blowing device for causing it while in said position to supply cooling air to an article within the mold during a predetermined time interval, means operating after said time interval to impart an additional lengthwise movement to the rock shaft, and means carried by the rock arm operative after said additional movement of the rock shaft to hold an article that has been blown in the mold.
8. A machine for forming hollow glass articles comprising, in combination, a rotating mold carriage, a mold rotating therewith, a rock shaft mounted to travel with the mold carriage, a rock arm thereon, a blowing head on the rock shaft comprising an air cylinder and piston, an article holding disk carried by the piston, means for moving the rock shaft lengthwise to an intermediate position, means for causing said movement to rock the shaft and swing the blowing head to a position over the mold, means for applying air under pressure to said cylinder while in said position and projecting said holding disk into engagement with an article in the mold, means to supply air from said blowing head to said article, and means for imparting an additional lengthwise movement to the rock shaft and thereby applying holding pressure to said disk independently of the air supplied to the blowing head.

AUGUST KADOW. 125
